AUDLEY HART STOW, OF CHARLESTON, WEST VIRGINIA, ASSIGNOR, BY MESNE ASSIGNMENTS, TO SANFORD INVESTMENT COMPANY, OF WILMINGTON, DELAWARE, A CORPORATION OF DELAWARE

MINE CAR AND THE LIKE

Application filed November 9, 1921, Serial No. 514,041. Renewed February 4, 1930.

This invention relates to certain improvements in and relating to mine cars and the like; and the objects and nature of the invention will be readily understood by those skilled in the art in the light of the following explanations of the accompanying drawings, illustrating what I now believe to be the preferred mechanical expressions or embodiments from among other forms, constructions and arrangements within the spirit and scope of the invention.

In various industries, but particularly in coal mining, the lading is discharged from certain types of cars, by tipping such cars endwise. In practice, the heavily loaded cars are moved rapidly to the dumping point and more or less quickly stopped at such point in preparation for the dumping operation. This sudden stopping of a heavy car, 20 in rapid motion, necessarily results in considerable shock and strain, both to the car and to the dumping structure. It is an object of my invention to cushion the shock and strain incidental to this more or less sudden halting of the car.

With this and other objects in view, the invention consists in certain novel features in construction and in combinations and arrangements as more fully and particularly 30 set forth and pointed out hereinafter.

Referring to the accompanying drawings:

Fig. 1 diagrammatically illustrates in side elevation, a common type of mine car and dumping apparatus, dotted lines indicate the 25 car and dumping apparatus in dumping position, the spokes and hubs of the car wheels being omitted.

Fig. 2 is a detail side elevation of a portion of a car embodying my invention.

Fig. 3 diagrammatically illustrates a car 40 embodying my invention and dumping apparatus, in side elevation, dotted lines indicating the cushioning movement of the car body and load, the car wheels being indicated by circles.

Fig. 4 shows in side elevation, a car embodying another form of my invention, the dumping apparatus being diagrammatically illustrated, and the car wheels indicated by 50 circles.

Fig. 5 is a detail section on the line 5—5, Fig. 4.

Fig. 6 is a detail inner side elevation of a portion of a side sill of the car of Fig. 4, showing an axle boxing of said car.

Fig. 7 shows a portion of said side sill as drilled or otherwise prepared to receive said boxing.

Fig. 8 is a top view of the boxing of Fig. 6, the sill being indicated by dotted lines.

Fig. 9 is a detail elevation of the boxing of Fig. 6, showing the side thereof that fits the sill.

Fig. 10 is a detail side elevation of a portion of a car sill provided with an axle boxing embodying provision for lubricating the car axle.

Fig. 11 is a detail elevation of the portion of the sill that receives the boxing of Fig. 10.

Fig. 12 is a detail top view of the boxing of Fig. 10, the sill being indicated by dotted lines.

Fig. 13 is a section on the line 13—13, Fig. 10.

Fig. 14 is a section longitudinally of a side sill (shown by dotted lines) showing inner and outer aligned boxings.

Fig. 1 has been introduced to clearly indicate the dumping means usually employed for dumping the common type of end dump cars, one of which is diagrammatically illustrated, to make plain the shock to which such cars and the dumping apparatus are subjected.

In Fig. 1 the well known car indicated embodies the car body 1 having bottom 12 to which the depending axle boxings 8 are secured. These boxings have cylindrical bearings receiving the axles 9 of the car wheels 7.

The open or dumping end of the car body is normally closed by a vertically swingable end gate having forwardly projecting or exposed hook 2. The well known dumping apparatus shown, comprises vertically tiltable track section 6 forming the "dump," mounted 90 to rock on the transverse axis 10, and provided with car counterweight 11, usually hung from the rear or long end of the dump by rod or other hanging support 13. The front ends of the rails of the dump are 95

to 100

curved upwardly to form hooks or so-called "horns" 6—1 to stop the forward movement of the car on the dump and to in effect uphold the car during the dumping operation.

5 The horns of the dump are shown above the tipple chute 5 onto which the car lading is delivered from the tilted car.

The end gate of the car is controlled by the swinging hook 4, which engages projection 2 10 of said gate, to expose the open end of the car as the car is tilted, as is well understood by those skilled in the art.

The radius of the curved rail ends or horns 6—1 is usually approximately the same as 15 the radius of the front car wheel treads, which engage the horns to stop the car. The mine cars with their heavy loads, travel more or less rapidly onto the dump and consequently are brought to a sudden halt when 20 the car front wheels engage the horns with resulting tremendous shocks and strains on the car and dump structures.

Now, it is the purpose of my invention to 25 approximately absorb this shock by providing for continued cushioning or lifting movement of the car body and its load when the front car wheels have been suddenly stopped by said horns. This result is accomplished approximately by gradually absorbing the 30 inertia of the car body—the load—in an effort to lift the load independently of the stationary front car wheels. This result can be accomplished by various constructions or arrangements, but I prefer to employ such more 35 or less loose or free connection or coupling between the front body supporting car wheels and the body as will enable the body to climb forwardly and upwardly, with respect to the front wheels, to gradually lift the load and 40 absorb the inertia of the forwardly moving mass, when the front wheels of the forwardly moving car are suddenly stopped by engagement with the horns of the dump.

In the common form of car, indicated by 45 Fig. 1, the axles 9 fit more or less snugly in the boxings 8 and no provision is made for relative fore and aft or longitudinal movement between the car body and front wheels, and on engagement of the front wheels with 50 the horns, the car body—the load—is suddenly halted simultaneously with the halting of the front wheels; the entire moving mass as a unit is halted by the horns with a consequent tremendous impact.

55 In Fig. 3 I show the car construction of Fig. 1 equipped with an exceedingly simple embodiment of my present invention, which consists in the provision of downwardly and rearwardly elongated axle receiving slots, 60 apertures or bearings 14^a, in the front axle boxings 14 to receive the front axle 9 and permit limited upward and forward movement of the load—the car body and lading therein—with respect to the front wheel axle.

65 In the structure of Fig. 3, the front boxing

14 and the rear boxing 8 are fixed to and depend from the plank floor or other car bottom 12. The axle receiving aperture or bearings of the rear boxings 8 are cylindrical to more or less closely receive the cylindrical portions of the rear axles 9 as in Fig. 1. Hence, 70 when the front wheels of the moving car of Fig. 3, are halted by the dumper horns, the inertia of the load will carry the car body and the rear wheels forwardly, as indicated by 75 dotted lines, and this forward movement will be against the weight of the load which will be lifted at its forward portion as indicated by dotted lines, Fig. 3, while the front wheels are held down and against forward movement of the horns. 80

The upper and lower ends of the elongated apertures or bearings 14^a are semi-circular to conform to the cylindrical portion of the axle in the bearing and the width of each bearing 85 between its parallel longitudinal edge walls is approximately equal to the diameter of the cylindrical portion of the axle in said bearing. The length of each elongated bearing aperture 14^a is in this instance, slightly less than 90 twice the diameter of the cylindrical portion of the axle therein, although, of course, the length of the bearing can be varied to suit conditions and requirements.

The angle of inclination of the elongated 95 bearings can also be varied to suit conditions and requirements, although the angle of the longitudinal axis of the bearing aperture with respect to the general plane, or direction, 100 of the track is preferably about forty-five degrees, or say somewhere between thirty and sixty degrees, so that the longitudinal walls thereof will have a wedging or cam action on the wheel axle in lifting the load under the forward longitudinal thrust or impetus of the 105 load when the front wheels are suddenly halted.

From the foregoing explanation, it will be 110 evident that the axle journal bearing is to be elongated on such a slope or pitch or inclination, that it acts as a gravity shock absorber, and the slope or inclination may therefore be termed a gravity dumping shock absorbing slope. In Fig. 6, the aperture 14^b represents the elongated axle journal bearing, which 115 registers with the aperture or opening 20, in Fig. 7, on the side beam 15.

As viewed sidewise of the car, see Fig. 4, 120 the axle journal bearing, as above, is elongated, but in neither a vertical nor in a horizontal direction. The direction of elongation may therefore be somewhat more specifically described as diagonal, as it appears in a side view of the car. My improved axle journal bearing may therefore also be designated as a diagonally elongated axle journal bearing. 125

The weight of the load, i. e. the car and its lading, normally maintains the car at its limit of downward movement with the semi-cylindrical upper ends of the elongated bearings 130

resting on the car axle, see 9, Fig. 2, to transmit the load to the axle through extensive area bearing surfaces thereon.

When the car moves rapidly forward and 5 the front wheels are suddenly halted by the dumper horns, the momentum of the load tends to carry the car longitudinally forward, and this force is translated by the inclined bearing apertures into a forward and upward 10 lifting movement, which if of sufficient power, continues until the semi-cylindrical lower end walls of the elongated bearings strike the axle, see position 9' indicated by dotted lines, Fig. 2, whereupon the independent forward lift- 15 ing movement of the car body is halted. The force of the impact being then exhausted, the car drops back and down to normal position with the semi-cylindrical top walls of the bearings again resting on the axle to carry 20 the load. The speed of the car at the time of the impact determines the speed of the upward and forward impact cushioning movement of the car with respect to the front wheel axis, under the action of the load lifting connection 25 between the front wheel axis and the car, and hence the cushioning effect is automatically proportioned to the speed of the impact.

In this connection, it will be noted that the 30 force of the impact is substantially absorbed or cushioned in the act of lifting the load, and that consequently the blow or impact of the lower ends of the bearings against the front wheel axis is substantially reduced approximately to a negligible shock and furthermore, distorting injury to the axle and lower ends of the bearings, is substantially avoided because of the extensive semi-cylindrical concentric areas of the axle and lower 40 bearing ends that come into engagement. The loose or load lifting connection between the car and wheel axle also performs an important function, in that independent drop of the wheels with respect to the car body is permitted which is of utility and advantage in preventing derailment when traveling over uneven tracks. The wheels can thus drop to follow unevenness in the tracks and thereby prevent the wheels from jumping the track. 45 This action takes place even where the loose lifting connection is established as in Fig. 3, between the body and front axle only, but in the preferred construction the loose load lifting connection is established between the 50 body and all of the car supporting wheels, see Fig. 4, although I do not wish to so limit the broad features of my invention.

The car of Fig. 4 embodies a traction truck comprising I beam longitudinal side sills 15 to the lower flanges of which the car floor or bottom 16 is secured, and to which the leading confining body 1 is also secured. In this car, the axles 9 are arranged above the car floor and extend through the side sills 15, the 60 vertical webs of which are provided with

transverse intermediate openings or apertures 20 to receive the axles. These apertures are inclined downwardly and rearwardly and formed approximately the same as elongated bearings 14^a, to perform the same functions 70 in providing the loose load lifting connection between body and wheel axle. However, I prefer that the webs of the side sills do not in themselves form or constitute the bearings for the wheel axles, and hence I preferably 75 provide axle boxings supported by said sills and embodying inclined bearing apertures 14^b, registering with the apertures 20 in the sill webs.

In the examples shown by Figs. 4 to 14, 80 each axle boxing 14-1 consists of a metal block arranged at the inner side of a side sill and fitted between and abutting the top and bottom flanges of the I beam and having a vertical side or end face 14-2 fitting against 85 the inner vertical face of the web of said beam. The opposite front and rear end portions of this block or boxing in this particular example, are shown formed integral with lugs or bosses 14-3 projecting laterally from 90 the vertical face 14-2 to snugly enter transverse holes 19 formed therefor in the vertical web of the I beam. The length of each boss 14-3 is approximately equal to the thickness of said web so that the outer end faces of the 95 bosses are approximately flush with the vertical outer face of the web to receive relatively large washers 17 against the outer faces of which attaching rivets 18 abut. The boxings are formed with rivet holes 21 to receive said 100 rivets. The boxings thus longitudinally interlock with the I beams and are rigidly fixed thereto by the rivets 18, as will be readily understood from the drawings. Of course, the equivalent of rivets 18 can be employed 105 to secure the boxings to the car side sills. Instead of washers, as shown in Fig. 14, an outside secondary boxing 14-4 can be arranged at the outer side face of the I beam sill to receive the fastening bolts or rivets 18. This 110 outside boxing intervenes between the car wheel hub and the outer vertical face of the I beam web and is formed with an elongated bearing aperture registering with the aperture 14^b of the boxing 14-1. In this instance, 115 I show the secondary boxing 14-4 interlocking with the I-beam through the medium of bosses 14-5 integral with boxing 14-4 and entering the holes 19 of the beam 15. The secondary boxing 14-4 is particularly intended 120 for use where roller bearing car wheels are employed to provide the additional support then required for the axle particularly under dumping shocks, even when cushioned by the 125 inclined bearing apertures.

If so desired, the boxing 14-1 can be laterally enlarged to provide holes for bolts or rivets 18-1 in addition to the bolts or rivets 18 (Figs. 10, 12) and for such enlarged box- 130

ing, the I beam web will be formed with the additional bolt or rivet holes 19'.

The boxing can provide for lubrication of the bearing surfaces engaged by the axle within the elongated bearing aperture. Various means can be provided for this purpose. For instance, in Figs. 10, 12, and 13, I show the boxing 14-1 enlarged to provide an internal oil waste chamber 25 peculiarly located with respect to the elongated bearing aperture and the normal position of the axle therein. This oil waste chamber is arranged in the upper part of the boxing above the elongated bearing aperture and above the axle. The chamber has a top filling opening normally closed by the top horizontal cover 23 arranged on top of the boxing and swingable on bolt 24. The chamber is open at the bottom to the axle, when in normal position. This bottom opening of the chamber is located midway the upper portion of the bearing surface and exposes the top of the axle to the lubricating material.

It is of advantage in mine car practice, to keep the axle lubricated within the bearing boxings so that the axle is free to rotate at all times, and such lubricated freely rotatable axle is particularly advantageous should the wheel hubs become dry and increase the frictional engagement thereof with the axle.

If so desired, the inner ends of the elongated bearing apertures in the boxings, can be covered to approximately exclude dust and grit, by dust guards mounted on the axles. For this purpose, I show vertical plates or collars 26, secured to the axle by set screws 27 (Fig. 5).

An I beam is not seriously weakened by removal of a reasonable quantity of material at or near the neutral axis of its web (see Figs. 7, 11) but in this instance, the weakened portion of the beam is braced by the boxing fitted therein and fixed thereto.

The bearing boxings which may be either inside or outside boxings, or combination of both, interlock with the car sills 15 (through bosses 14-3 and holes 19), among other reasons, for the purpose of taking up the shock between the boxings and sill when the front wheels of the car are suddenly stopped, and to relieve the securing bolts or rivets from shearing action to which they might otherwise be subjected.

The several forms of boxings, Figs. 4 to 13 inclusive, may all be termed inside boxings in that they are placed on the inner sides of the I-beams. The double boxings Fig. 14 may be said to consist of an inside and an outside boxing acting conjointly as a compound boxing. What have just been described as inside boxings, may of course be reversed, and placed on the outside of the I-beams. Evidently, what has been described as the inside boxing in Fig. 14, can be reversed and placed on the outside of the I-beam side sills.

What has been herein termed the boxing vertical side or end face 14-2, Fig. 9, may also be termed the vertical attaching face, as that is one of its functions.

The side sills 15, Fig. 4, evidently carry the entire weight of the car and its lading, and said sills are carried by the axle boxings. It is therefore evident that the boxing face bosses 14-3, are so designed as to not only resist the dumping shear, but also to carry the side sills and their load, without any shearing action whatever on the attaching rivets 18. These face bosses, may also be termed dumping shock resisting and side sill supporting bosses.

It is also to be noted, that the upper outer edge of the boxing proper 14-1, bears against the under inner side of the upper flange of the structural steel side sill 15. My improved boxing therefore, may also be described as having horizontal side sill flange bearing faces.

The bottom, 16, forming a part of Fig. 5 of the drawings is not a part of the subject-matter of this application. It forms a part of the subject-matter of my pending application for Letters Patent, Serial Number 289,190, filed April 11, 1919, for a "Mine car"; and my application for Letters Patent Serial Number 424,132, filed November 15, 1920, for "Mine or other cars."

It is evident that various changes, modifications, additions and departures might be resorted to without departing from the spirit and scope of my invention and hence I do not wish to limit myself to the exact disclosures hereof.

What I claim is:

1. A mine car and the like, comprising a lading supporting and retaining body, a wheeled support therefor including front wheels, and downwardly and rearwardly inclined elongated bearings for the wheel axle, said axle normally located at the upper ends of said bearings.

2. A mine car and the like having wheel axle bearing apertures elongated and inclined at an angle of approximately forty five degrees, the axle normally located at the upper ends of said apertures.

3. In a car, in combination, longitudinal supporting side sills, axle boxings within the side sills and having elongated axle bearings on a gravity dumping shock absorbing slope, rotary wheeled car axles extending through the sills and boxings and located in said bearings to cooperate with said slopes, and means for retaining said boxings in working positions within said sills.

4. A mine car having opposite side elongated bearings forming gravity dumping shock absorbing slopes, and car supporting wheeled axles including an axle extending through said bearings and cooperating with said slopes.

5. In mine and other cars, a wheeled rotary axle boxing including a diagonally elongated axle journal bearing.
6. In mine and other cars, in combination, 5 a wheeled rotary axle boxing including a diagonally elongated axle journal bearing and a vertical attaching face.
7. In mine and other cars, in combination, 10 a longitudinal supporting flanged metal side beam and a wheeled rotary axle boxing including a diagonally elongated axle journal bearing.
- 10 8. In mine and other cars, in combination, a longitudinal supporting flanged metal side beam, and a wheeled rotary axle boxing including a diagonally elongated axle journal bearing and an attaching face.
9. In mine and other cars, in combination, 15 a longitudinal supporting flanged metal side beam, and a wheeled rotary axle boxing including a diagonally elongated axle journal bearing and a vertical attaching face.
- 20 10. In mine and other cars, in combination, a longitudinal supporting flanged metal side beam, and a wheeled rotary axle boxing including a diagonally elongated axle journal bearing, a vertical attaching face having a lateral boss separate and apart from said axle bearing.
- 25 11. In mine and other cars, in combination, a longitudinal supporting flanged metal side beam, a wheeled rotary axle boxing including a diagonally elongated axle journal bearing and a vertical attaching face having a lateral boss separate and apart from said axle bearing, together with a lateral boss receiving aperture in said side beam.
- 30 12. In mine and other cars, in combination, a longitudinal supporting flanged metal side beam, and a wheeled rotary axle boxing including a diagonally elongated axle journal bearing, an attaching face, and an oil waste chamber.
- 35 13. In mine and other cars, in combination, 45 a longitudinal supporting flanged metal side beam, a wheeled rotary car axle intermediate the top and bottom flanges of said side beam, together with a rotary axle boxing including a diagonally elongated axle journal bearing, an attaching face, and an oil waste chamber over said car axle.
- 40 14. In mine and other cars, a wheeled rotary axle boxing consisting of an integral structure including a diagonally elongated axle journal bearing and an attaching face.
- 45 15. In mine and other cars, a wheeled rotary axle boxing consisting of an integral structure including a diagonally elongated axle journal bearing and a vertical attaching face.
- 50 16. In mine and other cars, in combination, a longitudinal supporting flanged metal side beam, and a wheeled rotary axle boxing consisting of an integral structure including a 55 diagonally elongated axle journal bearing.
17. In mine and other cars, in combination, a longitudinal supporting flanged metal side beam, and a wheeled rotary axle boxing consisting of an integral structure including a diagonally elongated axle journal bearing and an attaching face.
18. In mine and other cars, in combination, 70 a longitudinal supporting flanged metal side beam, and a wheeled rotary axle boxing consisting of an integral structure including a diagonally elongated axle journal bearing and a vertical attaching face.
19. In mine and other cars, in combination, 75 a longitudinal supporting flanged metal side beam, and a wheeled rotary axle boxing consisting of an integral structure including a diagonally elongated axle journal bearing, a vertical attaching face, and a lateral boss separate and apart from said axle bearing.
20. In mine and other cars, in combination, 80 a longitudinal supporting flanged metal side beam, a wheeled rotary axle boxing consisting of an integral structure including a diagonally elongated axle journal bearing, a vertical attaching face and a lateral boss 85 separate and apart from said axle bearing, together with a lateral boss receiving aperture in said side beam.
21. In mine and other cars, in combination, 85 a longitudinal supporting flanged metal side beam, a wheeled rotary axle boxing consisting of an integral structure including a diagonally elongated axle journal bearing and an attaching face, together with a wheeled rotary car axle and an axle journal bearing dust guard mounted on said axle.
22. In mine and other cars, in combination, 90 a longitudinal supporting flanged metal side beam, and a wheeled rotary axle boxing consisting of an integral structure including a diagonally elongated axle journal bearing, an attaching face, and an oil waste chamber.
23. In mine and other cars, in combination, 95 a longitudinal supporting flanged metal side beam, and a wheeled rotary axle boxing consisting of an integral structure including a diagonally elongated axle journal bearing, an attaching face, and an oil waste chamber located over said axle journal bearing.
24. In mine and other cars, the combination, 100 of, a longitudinal supporting flanged metal side beam and a wheeled rotary axle boxing secured together, said axle boxing consisting of an integral structure including, a diagonally elongated axle journal bearing and an attaching face.
25. In mine and other cars, the combination, 105 of, a longitudinal supporting flanged metal side beam and a wheeled rotary axle boxing secured together, said axle boxing consisting of an integral structure including, a diagonally elongated axle journal bearing and a vertical attaching face.
26. In mine and other cars, the combination, 110 of, a longitudinal supporting flanged metal side beam and a wheeled rotary axle boxing secured together, said axle boxing consisting of an integral structure including, a diagonally elongated axle journal bearing and a vertical attaching face.

- metal side beam and a wheeled rotary axle boxing secured together, said axle boxing consisting of an integral structure including, a diagonally elongated axle journal bearing, a vertical attaching face and a lateral boss separate and apart from the axle journal bearing. 5
27. In mine and other cars, the combination of, a longitudinal supporting flanged metal side beam and a wheeled rotary axle boxing secured together, said axle boxing consisting of an integral structure including, a diagonally elongated axle journal bearing, a vertical attaching face and a lateral boss separate and apart from the axle journal bearing, together with a boss receiving aperture in the web plate of said side beam. 10
28. In mine and other cars, the combination of, a longitudinal supporting flanged metal side beam and a wheeled rotary axle boxing secured together, said axle boxing consisting of an integral structure including a diagonally elongated axle journal bearing 20 and a vertical attaching face, together with a dust guard to said axle journal bearing. 25
29. In mine and other cars, the combination of, a longitudinal supporting flanged metal side beam and a wheeled rotary axle boxing secured together, said axle boxing consisting of an integral structure including a diagonally elongated axle journal bearing and a vertical attaching face, a wheeled rotary car axle, and a dust guard for said 30 elongated axle bearing and mounted on said 35 axle. 40
30. In mine and other cars, the combination of, a longitudinal supporting flanged metal side beam and a wheeled rotary axle boxing secured together, said axle boxing consisting of an integral structure including a diagonally elongated axle journal bearing, a vertical attaching face and an oil waste chamber. 45
31. In mine and other cars, the combination of, a longitudinal supporting flanged metal side beam and a wheeled rotary axle boxing secured together, said axle boxing consisting of an integral structure including, a diagonally elongated axle journal bearing, a vertical attaching face and an oil waste chamber located over said axle journal bearing. 50
32. In mine and other cars, the combination of, a longitudinal supporting flanged metal side beam and opposite wheeled rotary axle journal boxings all secured together, said axle boxings consisting of integral structures including diagonally elongated axle 55 journal bearings registering with each other, and vertical attaching faces. 60
33. In mine and other cars, the combination of a side beam, a car axle journal boxing including a diagonally elongated axle bearing, said bearing being elongated down- 65
- wardly and rearwardly, together with a car wheel rotary axle operating within said elongated axle bearing. 70
34. In mine and other cars, the combination of a car axle journal boxing including a diagonally elongated axle journal bearing, said bearing being elongated downwardly and rearwardly, together with a car wheel rotary axle operating within said elongated axle bearing. 75
35. In mine and other cars, the combination of a car axle journal boxing including a diagonally elongated axle bearing, together with a car wheel rotary axle operating within said elongated axle bearing. 80
36. A mine car and the like comprising axles, wheels on the axles, a lading retaining body directly mounted on the axles, and means providing for impact-absorbing relative forward lifting movement of the body 85 with respect to said axles on sudden halting of the forward movement of the wheels and axles. 90
37. A mine car and the like, comprising axles and wheels on the axles, a lading body directly mounted on the axles, and a loose impact-cushioning load-lifting connection between the axles and the lading retaining body constructed and arranged to cause the body to continue forward with a lifting movement when the front wheels of the forward moving car are suddenly halted. 95
